DESIGN FOR A RANGE OR ANALOGOUS ARTICLE

Walter C. Lindemann and Richard Meiners, Milwaukee, Wis., assignors to A. J. Lindemann & Hoverson Company, a corporation of Wisconsin

Application January 20, 1940, Serial No. 89,604

Term of patent 14 years

To all whom it may concern:

Be it known that we, Walter C. Lindemann and Richard Meiners, citizens of the United States, residing in the city of Milwaukee, county of Milwaukee, and State of Wisconsin, have invented a new, original, and ornamental Design for a Range or Analogous Article, of which the following is a specification, reference being had to the accompanying drawing forming a part thereof.

The figure is a perspective view of a range or analogous article showing my design. The sides of the range not shown are substantially plain.

We claim:

The ornamental design for a range or analogous article, as shown and described.

WALTER C. LINDEMANN.
RICHARD MEINERS.
